UNITED STATES PATENT OFFICE.

ANDREW R. K. LAUDER, OF SCHENECTADY, NEW YORK, ASSIGNOR TO GENERAL ELECTRIC COMPANY, A CORPORATION OF NEW YORK.

TROLLEY-CONTACT.

No. 906,038.

Specification of Letters Patent.

Patented Dec. 8, 1908.

Application filed March 27, 1908. Serial No. 423,540.

To all whom it may concern:

Be it known that I, ANDREW R. K. LAUDER, a citizen of the United States, residing at Schenectady, county of Schenectady, State of New York, have invented certain new and useful Improvements in Trolley-Contacts, of which the following is a specification.

My invention relates to trolley contacts for use in connection with signal systems on electric roads, and consists of an improvement in the trolley contact described in an application filed by L. A. Hawkins, December 31, 1907, Serial No. 408,764, assigned to the General Electric Company. In that application is described a trolley contact comprising a long, flat, flexible, continuous strip of conducting material supported in a horizontal plane directly above but separated from the trolley-wire and adapted to be engaged by the rims of the flanges of a trolley-wheel in passing.

My invention consists, in the addition to a contact thus arranged, of a continuous undulating strip of resilient material pressed down upon the conducting strip at a plurality of points, so as to exert a distributed yielding downward pressure to hold the contact strip in engagement with the passing trolley-wheel. The resilient strip is preferably secured against horizontal movement at one end only.

My invention is particularly advantageous for a contact intended for high-speed operation.

My invention will best be understood by reference to the accompanying drawings, in which

Figure 1 shows a side elevation of a trolley contact of the type to which my invention relates; Fig. 2 is an enlarged longitudinal sectional side elevation of the same showing the undulating member arranged in accordance with my invention; Fig. 3 is an end elevation of the trolley contact on the scale of Fig. 2; and Fig. 4 shows a cross-sectional, transverse view of the contact on a larger scale.

In the drawings, A represents the trolley-wire, and B B insulating ears or hangers of standard construction.

C represent a pair of supporting members in the form of light angle-beams extending parallel to and slightly above the trolley-wire on opposite sides of the wire.

These angle-beams are provided at their ends with spacing blocks D, and carry a sheet-metal inclosing cover E, which may be riveted or bolted to the supporting members C.

F F represent straps secured to the spacing blocks D, by means of which the angle-beams are supported from the hangers B B.

G represents a thin, flexible strip of conducting material, such as hard rolled copper or phosphor-bronze, which rests on, and is supported by, the angle-beams C C.

At the end of the contact which the trolley-wheel approaches, which is shown as a left-hand end in Fig. 2, the strip G is given a gradual upward incline, and is fastened at its end to the block D by means of clamping blocks H H, shown in Fig. 3. The outgoing end of the strip G is not fastened, but is given an upward incline, as shown at the right-hand end of Fig. 2, so that a trolley-wheel may pass under it from right to left, without danger of damaging the contact strip, and also so that there will be no tendency for the right-hand end of the strip to flap when the trolley-wheel passes under it rapidly from left to right.

A binding post I may be secured to the block D, to which the strip G is fastened, so as to conduct the current from the strip G to the signal mechanism.

The construction, so far as described, is the same as that disclosed in application, Serial No. 408,764, above referred to. The novel feature in the present construction is shown at K in Figs. 2 and 4. This member K consists of a continuous undulating strip of resilient material, such as spring steel, which is inserted between the contact-strip G and the cover E. This resilient strip bears on both the contact strip and the cover at a plurality of points, so that the cover serves as means for pressing the resilient strip K downward on the contact strip G, and causing it to exert a distributed, yielding, downward pressure on the contact strip. The strip K is clamped between the contact strip G and the spacing block D at the entering-end of the contact, as shown in Figs. 2 and 3, but otherwise is left free to move horizontally. Its right-hand end, as viewed in Fig. 2, is loosely supported by a member L fastened to the spacing block D.

The operation of the contact and the function of the resilient strip K will be clear from the above description. The trolley-

wheel approaches the contact from the left-hand end, as viewed in Fig. 2, and the rims of its flanges engage the contact strip between the point of attachment of the strip to the spacing block D and the point where the strip first touches the angle-beams C. This point of engagement varies somewhat with the depth of groove on the trolley-wheel. In Fig. 4 a trolley-wheel L is shown entering the contact and about to engage the contact strip. The incline of the strip is made so gradual that no shock occurs when the wheel engages the strip, even at very high speeds. As the wheel passes along the contact strip, the strip is held firmly in engagement with the rims of the wheel by the resilient strip K. The pressure is practically uniform, and there is no tendency to force the wheel from the trolley-wire, or to cause it to jump, even at the highest speeds, and the contact strip is prevented from being thrown upward by the trolley-wheel, so as momentarily to interrupt the circuit while the trolley-wheel is passing. Guide blocks M may be used to prevent sidewise displacement of the strip. The possibility of the free movement in a horizontal direction of all parts of the strip K, except at the end which the trolley-wheel approaches, enables the strip to yield more readily to impact, and causes it to maintain a more uniform pressure.

What I claim as new and desire to secure by Letters Patent of the United States, is—

1. A trolley contact comprising a long, flat, flexible, continuous strip of connecting material supported in a horizontal plane directly above but separated from the trolley-wire and adapted to be engaged by the rims of the flanges of a trolley-wheel in passing, a member above and parallel to said strip, and a continuous undulating strip of resilient material inserted between said conducting strip and said member and bearing against both at a plurality of points, said resilient strip extending substantially the length of said conducting strip.

2. A trolley contact comprising members extending parallel to and slightly above the trolley-wire on opposite sides thereof, a long, flat, flexible, continuous strip of conducting material resting on said members and adapted to be engaged by the rims of the flanges of a trolley-wheel in passing, a continuous undulating strip of resilient material extending substantially the length of said conducting strip and bearing thereon at a plurality of points, and means for pressing said resilient strip downward upon said conducting strip.

3. A trolley contact comprising a long, flat, flexible, continuous strip of conducting

material supported in a horizontal plane directly above but separated from the trolley-wire and adapted to be engaged by the rims of the flanges of a trolley-wheel in passing, a continuous undulating strip of resilient material extending substantially the length of said conducting strip and bearing thereon at a plurality of points, and means for pressing said resilient strip downward upon said conducting strip.

4. A trolley contact comprising supporting members extending parallel to and slightly above the trolley-wire on opposite sides thereof, a long, flat, flexible, continuous strip of conducting material resting on said members and adapted to be engaged by the rims of the flanges of a trolley-wheel in passing, a continuous undulating strip of resilient material extending substantially the length of said conducting strip and bearing thereon at a plurality of points, and a member secured to said supporting members above said resilient strip and serving both as an inclosing cover and a means for pressing said resilient strip downward upon said conducting strip.

5. A trolley contact comprising a long, flat, flexible, continuous strip of conducting material supported in a horizontal plane directly above but separated from the trolley-wire and adapted to be engaged by the rims of the flanges of a trolley-wheel in passing, a continuous undulating strip of resilient material extending substantially the length of said conducting strip and bearing thereon at a plurality of points, and means for pressing said resilient strip downward upon said conducting strip, said resilient strip being secured against horizontal movement at one end only.

6. A trolley contact comprising supporting members extending to and slightly above the trolley-wire on opposite sides thereof, a long, flat, flexible, continuous strip of conducting material resting on said members and adapted to be engaged by the rims of the flanges of a trolley-wheel in passing, a continuous undulating strip of resilient material extending substantially the length of said conducting strip and bearing thereon at a plurality of points, and means for pressing said resilient strip downward upon said conducting strip, said resilient strip being secured against horizontal movement at one end only.

In witness whereof, I have hereunto set my hand this 25th day of March, 1908.

ANDREW R. K. LAUDER.
